(57) **CLAIM**

The ornamental design for a siding element, as shown and described.

DESCRIPTION

FIG. 1 shows a perspective view of a siding element according to the principles of the present invention; FIG. 2 shows a front elevational view thereof, a rear elevational view not being shown as it is void of ornamentation;

FIG. 3 shows an end view thereof;

FIG. 4 shows a top plan view thereof; and,

FIG. 5 shows a bottom plan view thereof.

The siding element is broken in the center to indicate indeterminate length.
